UNITED STATES PATENT OFFICE.

JOHN HOLES, OF BELLWOOD, PENNSYLVANIA.

SMOKE-CONSUMING AND FUEL-SAVING CONSTRUCTION.

Application filed August 26, 1927. Serial No. 215,636.

This invention relates to a smoke-consuming and fuel-saving construction, and is illustrated, by way of example, in association with a common type of steam-boiler furnace.

5 The invention has for its main object the provision of an improved construction of this character, which will embody certain desired features of simplicity, efficiency and convenience, and which will be economical 10 in manufacture and durable in use.

In carrying out my improvements, provision is made for conducting the smoke from the smoke box into a cooling reservoir of copious size where the smoke will be cooled 15 and where the heavy matter and unconsumed products of combustion will be deposited; and provision is made for conducting the cooled and purified gases from said reservoir into a novel distributing device arranged in 20 the ash chamber underneath the fire grate where to distribute such gases in the stream of the usual air-draft passing upwardly through the fire bed so that they will be consumed. Additionally, provision is made 25 whereby, when it is desired or where the conditions of firing warrant the procedure, to divert the stream of cooled and purified gases, either wholly or partially, into the smoke stack.

30 Another object of the invention is the provision of an arrangement which will permit of the employment of simple, efficient and novel scraper means whereby thoroughly to clean the cooling reservoir whenever desired 35 without interrupting in any way the operation of the apparatus.

Other objects will appear hereinafter.

The invention consists in the novel features of construction and in the arrangement and 40 combination of parts hereinafter described and claimed.

The invention will be best understood by reference to the accompanying drawing forming a part of this specification, and in which:

45 Fig. 1 represents a front elevational view showing my improvements in association with an ordinary steam-boiler furnace;

Fig. 2 represents a side elevation partially in section with certain of the parts broken 50 away; and

Fig. 3 represents a detail view of the gas distributing device.

Although, in order to demonstrate the practicability of my invention, I have shown 55 a preferred embodiment thereof in associa-

tion with a steam-boiler furnace 10 of ordinary construction, it is to be understood that this association is by way of example only and that the use of my invention is not confined to this type of steam-boiler. In the 60 steam-boiler furnace 10, 11 designates the ash chamber, 12 the fire grate, 13 the fire box or combustion chamber, 14 the rear smoke box or passage to which the smoke passes from the fire box or combustion chamber, 15 the 65 fire tubes, 16 the front smoke box and 17 the smoke stack.

In its preferred form of construction, as illustrated in the accompanying drawing, my invention comprises a relatively large cooling reservoir consisting of a cylinder 18 having a front end 19 with a depending material discharging conduit 20, and having a rear end 21 with a similar depending material discharging conduit 22. The cylinder 18 is disposed in a water tank 23 so as to be surrounded by water with the depending conduits 20 and 22 protruding through the bottom 24 of the tank. For the exit ends of the depending conduits 20 and 22 suitable closures are 80 provided, those shown comprising openable hinged door or gate plates 25. The water tank 23 may be mounted in any suitable manner extraneously of the furnace and at an appreciable distance therefrom so that the water 85 within the tank will not be unduly heated because of proximity to the furnace. As illustrated in the drawing, it should be mounted in raised or elevated position to provide suitable clearance space through 90 which access may be readily had to the depending conduits for collecting material discharged therefrom.

With the front smoke box 16 there is constructed or otherwise provided a funnel-shaped extension designated in general by the numeral 26, the beginning of the wide-mouthed portion 27 of this extension being equally extensive with the cross-section of said smoke box, while the small or delivery 95 end 28 of said extension is of a size to effect a suitable union with an inlet pipe 29 which extends through the front end of the water tank and into the front end 19 of the cylinder, centrally thereof. Said extension 26 constitutes the front portion of the smoke box 16 and at a suitable point between its ends it is bent laterally as shown in order to join the inlet pipe 29 and at the same time to avoid obstructing 105 the space which the fireman must use in front 110

of the furnace. Any suitable power driven fan 30 (diagrammatically shown) may be incorporated near or at the small end of the extension to draw the smoke from the smoke box and force it into the cylinder.

Connected with the rear end 21 of the cylinder is an outlet pipe 31 leading through the rear end of the tank and joining a pipe 32 that extends into the lower portion of the 10 furnace, passes through the back wall 33 of the ash chamber and discharges into a gas distributing device 34 located in the ash chamber an appreciable distance below the fire grate 12. A power driven fan 35 (diagrammatically shown) is preferably incorporated at or near the junction of pipe 31 with pipe 32 to draw the gas from the cylinder and force it into the distributing device 34. Pipe 32 has a branch 36 that communicates with the 20 smoke stack 17 between the turn-valves 37 and 37' arranged therein for opening and closing communication with the outside atmosphere. Turn-valves 38 and 38' are arranged in the pipes 32 and 36, respectively, 25 for opening and closing communication therethrough.

A scraper device, is provided for the cylinder, the same comprising a ring 39 having snug sliding fit within the cylinder and provided at each end with a beveled scraping edge 40. Diametrically spanning the ring is a cross piece 41 to the center of which is affixed a handle 42 that extends centrally through a portion of the inlet pipe 29 and has 30 sliding fit in a bushing 43 associated therewith. On the exterior end of the handle is a suitable hand grip 44. By moving the scraper device to and fro, all heavy matter deposited on the interior of the cylinder will be stripped off and pushed into the depending conduits 20 and 22 from where such collected matter will fall to the ground or into suitable underplaced receptacles upon the opening of the door plates 25.

45 The gas distributing device 34 comprises a roof-shaped structure having two like sections 45 45 sloping from a central ridge 46, said sloping sections narrowing or receding toward the central ridge from their rear ends 50 47 to a front terminal 48. On issuing from the pipe 35, which preferably has its delivery end slightly upturned in the rear portion of the distributing device, the gases spread underneath the sloping sections to intermingle 55 with the air-draft and to be carried up therewith through the fire grate and into the fire bed where they are consumed. Through the provision of this distributing device, the gases cannot be wafted into the 60 fire bed in a concentrated stream and smother the fire at some particular region, but being spread about and intermingled with the oxygen of the air-draft they tend while being consumed to quicken the fire, accelerate combustion generally and bring about the con-

sumption of matter which is not ordinarily consumed. In this connection it is in place to state that an important feature of my improvements is the cooling reservoir which is kept surrounded by cooling water. Under 70 normal conditions, the most heat per unit of coal is obtained when the gases have been rendered substantially cool before being introduced into the ash chamber. For this reason the reservoir should be so copious in 75 size—having regard of course to the size of the furnace—and should be kept so cool that most of the heat will be extracted from the smoke. While cooling, the smoke gives up 80 its particles of soot, dust and all heavy matter, leaving only the cooled and purified gases which are highly inflammable.

In the operation of the exemplification shown, the turn-valves 37 and 38' being closed, the turn-valve 38 being open and the 85 fans 30 and 35 being in action, the hot smoke from the smoke box is conducted into the reservoir where it is cooled and where the heavy matter is deposited, and thence the cooled and purified gases are conducted into 90 the gas distributing device within the ash chamber. Upon closing the turn-valves 37' and 38 and opening the turn valves 38' and 37, the cooled and purified gases will be conducted to the outside atmosphere. To those 95 skilled in the art various arrangements of the turn-valves and fans will readily suggest themselves.

Water may be introduced into the tank by any suitable means. In the drawing, 49 designates a supply pipe through which water may be introduced into the tank and 50 designates an outlet pipe through which water may be conveniently withdrawn therefrom. If desired, the tank may be connected up with the 105 boiler and serve as a receptacle in which to give the water a preliminary heating before introducing it into the boiler; or the tank may be connected up as part of a water system and serves as the source of heated water 110 for any useful purpose.

Through the provision of the depending conduits 20 and 22 with their door plates, the heavy material which contains tar, creosote and other ingredients useful in the manufacture of by-products, may be readily collected in vessels placed under said conduits.

The apparatus of my invention may be incorporated in a steam-locomotive, in which event the cooling reservoir is preferably located in the water compartment of the tender while the gas distributing device is disposed in the ash pan below the fire grate.

While I have illustrated and described the preferred form of construction for carrying my invention into effect, this is capable of variation and modification without departing from the spirit of the invention. I, therefore, do not wish to be limited to the precise details of construction set forth but 125 130

desire to avail myself of such variations and modifications as come within the scope of the appended claims.

Having thus described my invention, what

5 I claim is:

1. A smoke-consuming construction comprising in combination with a boiler-furnace, a projecting funnel-shaped structure forming the head end of the smoke box and lessening in diameter from the smoke box until a smoke pipe is provided; a relatively large longitudinally extending smoke cooling cylinder receiving in one end thereof the exit end of said smoke pipe; and a roof-shaped 10 gas spreader extending forwardly from the rear wall of the ash pit of the boiler-furnace and receiving at its rear end the discharging end of a gas pipe which communicates with the other of the ends of said cylinder, the 15 ridge of said spreader being positioned closely beneath the fire grate whereby to distribute the cooled gases along a path closely beneath the fire grate.

2. A smoke-consuming construction comprising in combination with a boiler-furnace, a projecting funnel-shaped structure forming the head end of the smoke box and lessening in diameter from the smoke box until a smoke pipe is provided; a relatively large longitudinally extending smoke cooling cylinder having depending conduits with gate closed bottoms at its opposite ends; a roof-shaped gas spreader forwardly extending from the rear wall of the ash pit 20 of the boiler-furnace and having its ridge lying closely beneath the fire grate; a pipe extension from said smoke pipe discharging into one end of said cylinder; a gas pipe extending from the opposite end of said cylinder and discharging forwardly into said spreader; and means within the cylinder for removing incrustations from the inner face thereof into said conduits without obstructing the passage therethrough of smoke 25 from the exit end of said smoke pipe extension to the entrance of said gas pipe.

3. A smoke-consuming construction comprising in combination with a boiler-furnace, a projecting funnel-shaped structure forming the head end of the smoke box and lessening in diameter from the smoke box until a smoke pipe is provided; a relatively large longitudinally extending smoke cooling cylinder having at its opposite ends 30 depending conduits with gate closed bottoms; a roof-shaped gas spreader forwardly extending from the rear wall of the ash pit of the boiler-furnace and having its ridge lying closely beneath the fire grate; a pipe extension from said smoke pipe discharging into one end of said cylinder; a gas pipe extending from the opposite end of said cylinder and discharging forwardly into said spreader; means within the cylinder for removing incrustations from the inner face

thereof into said conduits without obstructing the passage therethrough of smoke; means in the smoke pipe for producing a forced draft from the smoke box to said cylinder; and means in said gas pipe for producing a forced draft from said cylinder to said spreader.

4. A smoke-consuming construction comprising in combination with a boiler-furnace, a projecting funnel-shaped structure forming the head end of the smoke box and lessening in diameter from the smoke box until a smoke pipe is provided; a relatively large longitudinally extending smoke cooling cylinder having at its opposite ends depending conduits with gate closed bottoms; a roof-shaped gas spreader forwardly extending from the rear wall of the ash pit of the boiler-furnace and having its ridge lying closely beneath the fire grate; a pipe extension from said smoke pipe discharging into one end of said cylinder; a gas pipe extending from the opposite end of said cylinder and discharging forwardly into said spreader; means within the cylinder for removing incrustations from the inner face thereof into said conduits without obstructing the passage therethrough of smoke; means in the smoke pipe for producing a forced draft from the smoke box to said cylinder; and means in said gas pipe for producing a forced draft from said cylinder to said spreader; and a pipe forming a communication between said gas pipe at a point beyond the forced draft means therein and the smoke stack of the smoke box, said pipe discharging 100 into the smoke stack between two regulating valves therein.

5. In a smoke-consuming construction, the combination with a longitudinally extending smoke cooling cylinder contained in a tank of water and having a smoke inlet pipe connected to one end thereof and an outlet pipe extending from the opposite end thereof, of a conduit depending from said cylinder and provided below said tank with a gate closed bottom; and a scraper device slidably fitting the inner periphery of said cylinder and operative between the ends thereof to strip off incrustations and push the same into said conduit, said scraper device having transverse 110 openings therein to allow the free passage of smoke from said inlet pipe to said outlet pipe.

6. In a smoke-consuming construction, the combination with an ash chamber and a fire grate, of a gas pipe discharging forwardly 115 into the rear end of the ash chamber; and a roof-shaped spreader extending forwardly from the rear wall of the ash chamber and receiving at its rear end the discharging end of said gas pipe, the ridge of said spreader positioned closely beneath the fire grate and its sloping sides receding forwardly and upwardly to said ridge whereby to distribute gas along a path closely beneath the fire grate.

7. In combination, a smoke box; an ash

chamber; a water tank; a longitudinally extending smoke cooling cylinder disposed in said tank to be surrounded by water; a smoke pipe connecting said smoke box with one end 5 of said cylinder and discharging into the latter; a gas distributing device in said ash chamber; a gas pipe leading from the opposite end of said cylinder to said distributing device and discharging thereinto; conduits 10 depending at the ends of said cylinder and protruding below said tank and having gate closed bottoms therebelow; a scraper device

slidably fitting the inner periphery of said cylinder and operative between the ends thereof to strip off deposited matter therein and push the same into said conduits; the said scraper device having transverse openings 15 therein to allow the free passage of smoke from the discharging end of said smoke pipe to the entrance end of said gas pipe. 20

In testimony whereof, I have signed my name to this specification.

JOHN HOLES.
